UNITED STATES PATENT OFFICE

164,386

COMBINED TREE HOLDER AND COIN RECEPTACLE

Carl Rose, Miami, Fla.

Application September 12, 1949, Serial No. 4,970

Term of patent 14 years

(Cl. D35—3)

To all whom it may concern:

Be it known that I, Carl Rose, a citizen of the United States, residing at Miami, county of Dade and State of Florida, have invented a new, original, and ornamental Design for a Combined Tree Holder and Coin Receptacle, of which the following is a specification, reference being had to the accompanying drawing, forming a part thereof.

Figure 1 is a front perspective view of a combined tree holder and coin receptacle showing my new design and.

I claim:

The ornamental design for a combined tree holder and coin receptacle, as shown.

CARL ROSE.
